Primary Examiner — Mary Ann Calabrese*Assistant Examiner* — Catherine Ho(74) *Attorney, Agent, or Firm* — Banner & Witcoff, Ltd.(57) **CLAIM**

The ornamental design for a power converter enclosure, as shown and described.

DESCRIPTION

FIG. 1 is a front perspective view of a power converter enclosure showing our new design,

FIG. 2 is a rear perspective view thereof,

FIG. 3 is a front elevational view thereof,

FIG. 4 is a rear elevational view thereof,

FIG. 5 is a left side elevational view thereof,

FIG. 6 is a right side elevational view thereof,

FIG. 7 is a top plan view thereof; and,

FIG. 8 is a bottom plan view thereof.

The broken lines in FIG. 8 show portions of the power converter enclosure which form no part of the claimed design.

1 Claim, 7 Drawing Sheets(56)
